UNITED STATES PATENT OFFICE

SALIM N. MALLOUK, OF BROOKLYN, NEW YORK

DESIGN FOR AN EMBROIDERED TABLE COVER OR THE LIKE

Application filed June 6, 1929. Serial No. 31,565. Term of patent 7 years.

To all whom it may concern:

Be it known that I, SALIM N. MALLOUK, a citizen of the United States of America, and a resident of the borough of Brooklyn, Kings County, city and State of New York, have invented a new, original, and ornamental Design for Embroidered Table Cover or the like, of which the following description, in connection with accompanying drawing, is a specification.

The single figure of the drawing is a plan view of a little more than a quarter section of the embroidered table cover, the quarter section being indicated by dot and dash lines. The representative illustration of the quarter section is repeated in the other three quarters in proper relation thereto.

I claim as my invention:

The ornamental design for an embroidered table cover or the like as shown and described.

SALIM N. MALLOUK.
